DESIGN FOR AN INDUCTOR HOUSING

Vernon Moore, Catonsville, Md., assignor to Bendifx Aviation Corporation, New York, N. Y., a corporation of Delaware

Application November 27, 1943, Serial No. 111,803

Term of patent 14 years

To all whom it may concern:

Be it known that I, Vernon Moore, a citizen of the United States, residing in Catonsville, Maryland, in the county of Baltimore, have invented a new, original, and ornamental Design for Inductor Housing, of which the following is a specification, reference being had to the accompanying drawing, forming a part thereof.

I claim:

The ornamental design for an inductor housing, as shown.

VERNON MOORE.
